UNITED STATES PATENT OFFICE

147,571

DESIGN FOR A FINGER RING

George P. Wagner, Edgewood, R. I., assignor to
Uncas Manufacturing Company, a corporation
of Rhode Island

Application August 9, 1946, Serial No. 132,369

Term of patent 14 years

(Cl. D45—10)

To all whom it may concern:

Be it known that I, George P. Wagner, a citizen of the United States, residing in Edgewood, county of Providence and State of Rhode Island, have invented a new, original, and ornamental Design for a Finger Ring, of which the following is a specification, reference being had to the accompanying drawing, forming a part thereof.

Fig. 1 is a top plan view showing my new design for a finger ring;

Fig. 2 is a side elevation; and

Fig. 3 is an edge view thereof.

The dominant part of the design is shown in full lines.

I claim:

The ornamental design for a finger ring, substantially as shown and described.

GEORGE P. WAGNER.
